ATTACHMENT FOR SEWING MACHINES

Victor J. Sigoda, Great Neck, N.Y., assignor to Man-Sew Corporation, New York, N.Y., a corporation of New York

Application November 3, 1952, Serial No. 318,463

5 Claims. (Cl. 112—134)

This invention relates to improvements in sewing machine ruffling attachments and more particularly to apparatus for producing a series of stitched, scallop-shaped ruffles or gathers of a type known in the trade as "Van Dyke" ruffling.

One of the principal purposes of the invention has been to provide an attachment which can be incorporated into the sewing machine without altering its basic structure and which may readily be removed therefrom without affecting the operation of the sewing machine.

It has also been a prime object to provide an attachment which may be mounted on the sewing machine in such position as to afford the operator a clear, unobstructed view of the work and which permits unhampered passage of the fabric materials being sewn under the arm of the machine. Such an arrangement makes possible application of scallop-shaped ruffling to any garment or fabric sections which can conveniently pass beneath the arm of the sewing machine. This also permits the sewing machine base to be free of all mechanism which would tend to disarrange or soil the work, which is an advantage when it is realized that the working parts of any high speed mechanical device require adequate lubrication.

A further object has been to provide a simple, effective and inexpensive attachment for sewing machines to produce scallop-shaped ruffling in the large scale manufacture of women's garments and analogous products, at a high rate of speed with uniformity of product and reliability of performance.

Other objects will in part appear and in part be obvious from the following detailed description of the presently preferred embodiment of the invention taken in conjunction with the drawings in which:

Fig. 1 is a front elevation of a zigzag sewing machine of well known make to which the attachment has been applied with one portion in vertical section showing how the oscillatory motion for producing the ruffling is developed at the drive-wheel;

Fig. 2 is a rear elevation of part of the machine illustrating the drive means for developing the reciprocating motion which effects the scalloping of the ruffling;

Fig. 3 is a cross-sectional view taken on line 3—3 of Fig. 1, showing further details of the construction of the mechanism which produces the scalloping of the ruffling;

Fig. 4 is a plan view of the machine with part of the arm broken away to show further details of the parts used to produce the scalloping of the ruffling, and having the vertical section of Fig. 1 sectioned in a horizontal plane to show further how the oscillatory motion which drives the ruffling mechanism is developed at the drive-wheel;

Fig. 5 is an end elevation at the needle-head end of the machine, with the cover-plate removed, illustrating the parts used for operating the ruffling blade;

Fig. 5A is an exploded view, in perspective, showing the structure and operating relationship of various of the parts of the mechanism which operate the ruffling blade, certain members being partly broken away for greater clarity; and

2

Fig. 6 is a plan view of a portion of the scalloped ruffling as it would be applied to a base or carrier fabric by means of the attachment in conjunction with the stitch-forming and work-feeding mechanisms of the sewing machine.

The attachment consists of two main sections, the mechanism for developing the ruffling and the mechanism for producing the lateral reciprocation of the material which results in the ruffles being scalloped as they are sewn together. Each of these main sections in turn consists of a drive mechanism and a material manipulating portion.

The machine generally

Referring to Fig. 1, the attachment as a whole is shown applied to a Singer type 143W1 machine. This machine 10 has the usual base 11, pedestal 12, overhanging arm 14, and the needle-head 15 which carries the needle-bar 16 and needle 17 and the vertically movable presser-foot bar 18 on which is mounted the presser-foot 19. The hook which cooperates with the needle to form the stitches and the feed-dog which coacts with the presser-foot shoe to feed the work are not shown, being so well known in the art as to require no further description of their structure or operation.

Extending horizontally within arm 14, as indicated in Fig. 3, is the usual main shaft 20 having drive-wheel 21 at one end and connected at the other end within needle-head 15 with the usual mechanism for reciprocating the needle-bar 16 vertically. The needle-bar 16 is carried in a laterally shiftable guide-frame 22 (partially shown in Fig. 1) pivoted at its upper end in the usual manner within needle-head 15. This guide-frame 22 is laterally shifted through pitman 23 which is vibrated from an adjustable eccentric of well known construction generally indicated at 24. The rotation of this eccentric produces the vibratory motion which shifts the needle from side-to-side to form zigzag stitches and, since it forms no part of this invention, no description need be given of its details of construction or the means for adjusting it. In passing however, it should be noted that the means for adjusting this eccentric permits the extent of the side-to-side vibration or the bight throw to be reduced to a point where the needle sews straight stitching without any zigzag effect. Accordingly, it can be appreciated that the invention to be described does not depend upon zigzag stitching for its effectiveness, although the many advantages of zigzag stitching make it preferable for use on soft materials or yielding materials such as net or tricot.

This eccentric is driven from main shaft 20 through a pair of spiral gears 25 and 26 (Fig. 3) which may have the usual ratio of 2 to 1 so that transverse shaft 28 rotates once for each two revolutions of main shaft 20, each rotation of the latter corresponding to one stitch.

Drive mechanism for the ruffling

55 A hollow eccentric block 29 is secured over the hub end of drive-wheel 21 and extends within the open side of a suitably formed housing 30 on the upper end of a supporting arm 31 which is rigidly bolted as at 32 to the base 11 of the machine. An eccentric stud 34 is screwed into the outer face of eccentric block 29 at a fixed distance radially off center which is selected to provide the desired maximum oscillation of the ruffling blade. Rock shaft 35 is suitably journaled at 36 in housing 30. Arm 38 is clamped to shaft 35 at its end within the housing. Pitman 39 links the end of arm 38 with the eccentric stud 34.

70 However it will be understood that eccentric block 29 and link 39 may be readily replaced with an eccentric and strap connection with arm 38 to produce oscillation of rock shaft 35.

The oscillation of rock shaft 35 produced by the opera-

tion of the sewing machine is transmitted to the ruffler producing mechanism which will now be described.

Ruffler producing mechanism

The usual face-plate which covers the end of the needle-head 15 is removed and a casting 40 which is substantially a counterpart of the face-plate is substituted and suitably secured to the needle-head. Casting 40 includes a housing section 41 which projects rearwardly from the plate section 42 with respect to the arm 14. The open side of this housing section 41 may be closed by a removable, thin, metal face-plate 43 so that all of the movable operating parts for the ruffling blade are completely concealed and protected, while permitting easy access thereto should occasion require.

The front lower end portion of casting 40 is formed with a suitable bearing 44 for a ruffler blade operating shaft 45. On the external end of shaft 45, a downwardly extending arm holder 46 is clamped, and arm 48, which extends downwardly toward the needle 17, is carried thereby. A stud shaft 49 is secured to arm 48 at its lowermost end. Pivotaly mounted on shaft 49 is a ruffling blade holder 50, to which is secured the tempered spring steel, toothed, ruffling blade 51. A suitable spring 52 yieldingly urges the toothed end of the ruffling blade upwardly upon the fabric material to be ruffled or gathered as it moves to the needle. The tension exerted by spring 52 may be regulated by loosening and retightening nut 53 which is threaded on stud shaft 49 and locks spring anchoring arm 54 in suitable position. It is to be understood that the other end of spring 52 is suitably anchored in an opening in ruffler blade holder 50.

Casting 40 is formed with a suitable bearing 55 for rock shaft 35 which has an angular bracket member 56 mounted on its end within the housing portion 41. Bracket member 56 has a shaft portion 58 normal to the axis of rotation of rock shaft 35. Upon this shaft portion 58 a block 59 is slidably mounted. Block 59 has a part slidably engaged in longitudinal slot 60 of a lever 61, the parts being arranged to permit relative angular movement between said lever and the shaft portion 58 of bracket member 56.

The lower end of slotted lever 61 is secured to an arm 62 which is clamped to the ruffler blade operating shaft 45 so that as rocking movement is imparted to rock shaft 35 from the eccentric drive mechanism previously described, oscillatory motion will be transmitted to the ruffling blade 51.

As previously explained, the radial distance off center of stud 34 on eccentric block 29 determines the maximum stroke of bracket 56. For the purpose of reducing this stroke to any desired degree, including rendering the ruffling blade practically inoperative, the position of slide block 59 may be adjusted relative to the upper end of slotted lever 61. The means for accomplishing this consists of rock shaft 64 suitably journaled in a bearing 65 in the side wall of housing 41. At the end of rock shaft 64 within the housing, the upper end of lever 66 is secured. The lower end of lever 66 is connected by link 68 with slide block 59.

To the end of rock shaft 64 outside the housing 41, a bifurcated lever 69 is fixed. As viewed in Fig. 2, arms 69a and 69b extend away from needle head 15 toward the viewer. Upper arm 69a is threaded to receive an adjustable thumbscrew 70. Boss 71 on the exterior wall of housing 41 serves as a stop for arm 69b and the end of thumbscrew 70.

Arm 66 is normally urged downwardly to draw slide block 59 into a position on shaft 58 at which there is maximum oscillatory motion imparted to the ruffling blade 51. Spring 72 is coiled about rock shaft 64 with end 73 bearing against needle-head 15 and with the other end 74, which comes off the top of spring 72 as viewed in Fig. 2, anchored in arm 75. When arm 75 is initially clamped on rock shaft 64, it is positioned so that spring

end 74 is drawn upwardly, uncoiling spring 72 and thus tending to rotate shaft 64 so that arm 66 is drawn downwardly. The torsion exerted on rock shaft 64 by spring 72 may be adjusted by unclamping and shifting the radial position of spring anchoring arm 75 on rock shaft 64. The extent to which rock shaft 64 may be rotated is limited by the end of thumbscrew 70 coming into contact with stop boss 71. Thus by adjusting thumbscrew 70 downwardly, the maximum oscillatory stroke of the ruffler blade may be reduced by degrees until practically no ruffling stroke is obtained, as the throw of the ruffler blade is in proportion to the distance of slide block 59 from the axis of rotation of rock shaft 35.

The fabric material which is to be ruffled and stitched together is fed through a guide 76 which is laterally reciprocated to produce the scalloped effect. This shifting is accomplished by the mechanism which will now be described.

Drive mechanism for laterally shifting the fabric guide

Transverse shaft 28 is somewhat longer than and replaces the corresponding shaft with which the machine is originally equipped. The extended end of this shaft passes through an opening in a gear train support-plate 78 which is fastened to the back of arm 14. Shaft 28 carries at its exterior end spur gear 79 engaged with a compound gear 80, having a larger toothed portion 81 in mesh with gear 79, and a smaller toothed portion 82 which is in mesh with a final, large gear 83 mounted on shaft 84. This gear train provides a further reduction from the rate of rotation of armshaft 20. In the parts illustrated, the ratio is three to one, which together with the reduction of two to one previously obtained through spiral gears 25 and 26, results in driven shaft 84 turning at one sixth the speed of armshaft 20.

Shaft 84 is journaled in support-plate 78 and carries an adjustable crank-block 85, suitably spaced from support-plate 78 by a bushing or hub 86. Block 85 has a radially disposed T-slot 87 in which stud 88 may be mounted at a predetermined distance from the axis of rotation. The distance selected determines the extent of reciprocation of pitman 90 which is pivotally mounted on stud 88. As the stud is moved toward the center of block 85, the stroke of arm 90 is progressively lessened, and at the center position, there is no reciprocation of pitman 90.

In the means shown in Figs. 1 and 3, stud 88 is fixed in its selected position in slot 87 by threading it through nut 89 so that the end of stud 88 bears against the bottom of the T-slot and nut 89 bears against the opposite wall of the T-slot.

Fabric guide shifting mechanism

Clamped on presser-foot bar 18 is a bearing-yoke 91 (Fig. 4) having two downwardly extending arms 92 and 93 which are bushed to act as journals for a laterally reciprocating slide-rod 94. Rod 95 is disposed parallel to slide-rod 94 and is secured in yoke 91 by set screw 96 and acts as an extended bearing and aligning guide for vertically disposed connecting-bar 98 which is also clamped to slide-bar 94 at 99. The upper end of bar 98 is either slotted or bored to permit some clearance about rod 95 as the bar is reciprocated laterally. Pitman 90 is pivotally connected with bar 98 at 100, and as pitman 90 is oscillated by the rotation of crank-block 85, slide-rod 94 is laterally reciprocated across the line of feed.

At its outer end slide-rod 94 has clamped to it a bent lever 101 to which the fabric strip material guide 76 and ruffling plate 77 are secured, as by soldering.

Operation of the attachment

The fabric strip which is to be ruffled or gathered is fed through guide 76 and under foot 19. A base or carrier fabric material may be used if desired, although it is not necessary. The wishes of the garment designer will

dictate whether it is used or not, as it is obvious that various decorative effects may be obtained by using different fabrics contrasting in either color or texture.

Operation of the machine will cause eccentric block 29 to rotate and in turn, ruffler blade 51 will begin to oscillate about its axis of rotation. The toothed end of the ruffler blade will engage the fabric strip emerging from guide 76, and as the ruffler blade oscillates toward the presser-foot 19 at any rate greater than the rearward feed stroke of the feed-dog, additional material will be fed under the shoe and will form a fold or gather. This folding or gathering action is generally timed to occur during the downward stroke of the needle so that the gather or fold will be fully formed just as the needle begins to penetrate the work, thereby holding the fold so that it may be secured by the subsequent stitch formation. The ruffler blade is normally retracted during this latter portion of the stitching cycle so that it will be in position to commence to form a new ruffle or gather on its next stroke toward the shoe.

It is well known that ruffling is produced only when the rate at which the ruffler blade advances the material is greater than the rate at which the feed members advance the work. It follows that increasing the throw of the ruffler blade will increase the depth of the ruffle or gather. As indicated previously, suitable adjustment of thumbscrew 70 will provide ruffling of any given depth within the maximum capabilities of the mechanism as constructed.

While the ruffling proceeds during the course of operation of the sewing machine, rotation of mainshaft 20 will cause crankblock 85 to rotate and vibrate pitman 90 which in turn will reciprocate slide-bar 94 and guide 76.

As guide 76 is shifted across the line of stitching and feeding, the ruffler will continue to form as described, but each succeeding ruffle will be laterally offset slightly from the preceding ruffle, producing an ornamental, undulating effect as indicated in Fig. 6.

In the specimen shown in that view, the ruffler blade was actuated to produce one ruffle for each stitch, but by substitution of other ruffler mechanisms, as for example that shown in Sigoda Patent 2,352,660, other ratios may be obtained.

While the invention has been described as illustrated in the present preferred embodiment, it is apparent that numerous detailed changes in construction might be made without departing from the spirit of the invention as defined in the claims.

What is claimed is:

1. A scalloped ruffler attachment for a sewing machine having a base; a main shaft; a needle head; a needle bar and a needle carried thereby and a presser foot bar having a presser foot carried by said head; means for reciprocating a ruffler blade downwardly toward said needle and a pivotally supported ruffler blade operated thereby; and a transverse shaft having a driving connection with the main shaft: said attachment including a support attachable to the machine; a shaft journaled in said support; means adapted to be connected to said machine transverse shaft for driving said attachment shaft; a bracket adapted to be clamped to said presser foot bar above the presser foot; a bar journaled in said bracket for reciprocation transversely of the line of stitching rearwardly of the needle when the attachment is mounted on the machine; a crank on said attachment shaft; a connecting rod joining the crank to said reciprocating bar; a ruffler plate and a strip fabric guide carried by said bar; said plate being adapted to extend upwardly in advance of said needle and arranged to be in the path of downward movement of said ruffler blade when the attachment is mounted on the machine; said guide having its outlet disposed above said plate in such position that the

strip emerging downwardly therefrom may be engaged between said plate and said blade as the latter is reciprocated in the operation of the machine; said attachment being supported wholly above said base when mounted on the machine.

- 5 2. An attachment according to claim 1 in which a downwardly and forwardly extending arm depending from said reciprocating bar supports the ruffler plate in advance of the needle and in which said plate also supports the strip fabric guide with its outlet disposed above that portion of said plate with which the ruffler blade engages to gather the fabric strip in the operation of the sewing machine when the attachment is mounted thereon.
- 10 3. A scalloped ruffler attachment for a sewing machine having a base; an arm above said base; a main shaft; a needle head; a needle bar and a needle carried thereby and a presser foot bar having a presser foot carried by said head; means for reciprocating a ruffler blade downwardly toward said needle and a pivotally supported ruffler blade operated thereby; and a transverse shaft having a driving connection with the main shaft: said attachment including a detachable plate adapted to be secured to and to depend from said machine arm; said plate having an opening through which the machine
- 15 20 transverse shaft may extend; an attachment shaft journaled in said detachable plate in parallel relationship to said machine transverse shaft when the said plate is mounted on the machine arm; means adapted to connect the machine transverse shaft and said attachment shaft
- 25 30 to drive the latter; a bearing member adapted to be attached to the machine arm; a rod journaled in said bearing member for reciprocation transversely of the line of stitching rearwardly of the needle when the attachment is mounted on the machine; a crank on said attachment
- 35 35 shaft; a connecting rod joining the crank to said reciprocating rod; a ruffler plate and a strip fabric guide carried by said rod; said plate being adapted to extend upwardly in advance of said needle and arranged to be in the path of downward movement of said ruffler blade when the attachment is mounted on the machine; said guide having its outlet disposed above said plate in such position that the strip emerging downwardly therefrom may be engaged between said plate and said blade as the latter is reciprocated in the operation of the machine; said attachment being supported wholly above said base when mounted on the machine.
- 40 45 4. An attachment in accordance with claim 3 in which a stationary bearing and aligning rod is carried by the bearing member when the latter is attached to the machine; said stationary rod being supported in parallel relation to the reciprocating rod journaled in said bearing member; together with a vertically disposed bar connected to said reciprocating rod; said bar having a portion constructed and arranged to bear against the stationary rod to prevent rotation of said reciprocating rod.
- 50 55 5. An attachment according to claim 4 in which a downwardly and forwardly extending arm is secured to one end of said reciprocating rod and supports the fabric guide in advance of the needle and wholly above the base of the machine.
